UNITED STATES PATENT OFFICE

WILBUR STANLEY LEWIS, OF LAKEWOOD, OHIO, ASSIGNOR TO THE NESTLE-LE MUR COMPANY, OF NEW YORK, N. Y., A CORPORATION OF OHIO

ELECTRIC HEATER

Application filed December 27, 1927, Serial No. 242,652. Renewed November 23, 1929.

This invention relates to an electric heater and is particularly adapted to tubular heaters such as are used in the permanent waving of human hair.

5 An object of the invention is to provide a heater which will be compact, neat in appearance and easily kept clean.

Another object is to provide a heater which may be manufactured of few and simple 10 parts and readily assembled.

Other objects will hereinafter appear.

The invention will be better understood from the description of one practical embodiment thereof illustrated in the accompanying drawing in which

15 Figure 1 is a perspective view of the completely assembled heater;

Figure 2 is a central longitudinal section thereof; and

20 Figure 3 is a diagrammatic representation of the electric circuits of three of the heaters.

As illustrated in Figures 1 and 2 the heater consists of an upper heater unit A and a lower heater unit B, each consisting of a hollow metallic shell containing a winding of resistance wire by which the heat is generated, the two units being spaced apart by a series of 25 pillars or the like, and surrounding central aligned cylindrical spaces in which the strand of hair or the like which is to be heated may be inserted.

The upper unit A consists of a central metallic tube 1, on the exterior of which resistance wire 2 is wound, the wires being suitably 30 insulated from each other and from the tube.

35 At the ends of the tube caps or rings 3 and 4 of generally U-shaped cross section are placed and support an outer tubular covering 5. The covering 5 is formed at one point, 40 adjacent the top, with an upwardly extending integral lug 6, and the cap 3 at this point is also formed with a corresponding lug 7, the two lugs when the parts are in assembled relation forming a short tubular projection 45 through which conducting cable 8 may be led to the interior of the unit.

Surrounding this tubular extension and attached thereto as by soldering, brasing, or the like, is a threaded ring 9 for the purpose 50 of retaining a tubular insulator 10 provided

with internal threads and supporting a conducting cable which leads to the interior of the heater.

The lower unit consists of a central tube 11 aligned with tube 1 above described, and upon which a second coil 12 of resistance wire constituting the lower heating element is wound. The upper end of the unit is closed by a cap 13, while the space between the outer periphery of this cap and the lower end of the tube 11 is enclosed within an ogival cover 14. Tubular pillars 15, shown as three in number, connect caps 4 and 13 by being brazed or welded thereto, or by having reduced ends extending through perforations 15 in the caps and being expanded or riveted over. Insulating conductor wires, as 16, supplying current to a coil 12 are led through the tubular pillars as shown.

25 The heater may be readily assembled, as follows:

Tubes 1 and 11 are inserted through the openings in caps 4 and 13 and the ends of the tubes expanded to lock the same to the inner flanges of these caps. Pillars 15 are 30 then interposed between the caps and secured thereto. The coils 2 and 12 are next wound upon the tubes and connected to the conducting cable 8. Next cover 14 is placed over tube 11, its upper end seating within cap 13, and the lower end of tube 11 is expanded to retain the same in place, and cover 5 is inserted 35 around tube 1 seating within cap 4, cap 3 is slid over the end of tube 1 with its outer flange overlying the upper end of tube 5, 40 and the upper end of tube 1 is expanded.

45 Of course, in assembling cap 3 and cover 5 the conductor 8 is positioned between the upwardly extending lugs and after these parts are secured in place ring 9 is slid over 50 the lugs and brazed thereto. Next, insulator 10 is slid down over conductor 8 and screwed onto ring 9, after which the outer end of the conductor may be connected in any suitable 55 manner with the apparatus which is to deliver 55 current thereto.

Figure 3 shows the circuit of three heaters and one manner in which the same may be connected to a source of electricity shown as a generator G. The generator supplies cur- 60

rent to two conductors 17 and 18 the first of which is provided with a switch 19 and connected to the adjacent ends of the coils 2 and 12 by wires 20. Conductor 18 is directly connected by wires 21 to the lower ends of coils 12 and connected through switch 22 and wires 23 to the upper ends of coils 2. It will be seen that when both switches are closed, coils 2 and 12 in each heater are connected in parallel and generate heat in both units of the heater. If it is desired to discontinue supplying heat to both units, switch 19 may be opened and all the current will be turned off, while it is desired to supply heat to units B only, switch 22 is opened and disconnects coils 2 from the source of current.

While I have described the illustrated embodiment of my invention in some particularity, obviously many changes and modifications may be made therein without departing from the spirit of the invention, and I, therefore, claim all such embodiments coming within the scope of the appended claims.

I claim:

25 1. A tubular heater comprising two axially spaced units, each consisting of a coil of conducting wire enclosed within a hollow annular shell, each shell including concentrically arranged inner and outer tubes and perforated caps and united together by the expansion of the ends of the inner tubes.

25 2. A heater consisting of two axially aligned units each consisting of a coil of wire enclosed within a shell each including a central tube, caps surrounding adjacent ends of said tubes and secured thereto by expansion of said ends, pillars connecting said caps, the caps being provided on their outer peripheries with flanges, tubular covers surrounding said tubes and seating within said flanges, the outer end of one cover being secured to its central tube by expansion of the outer end of the latter, and the outer end of the other cover being received under a flange on the 45 third cap, the inner edge of which is secured to its central tube by expansion of the end thereof.

30 3. A heater comprising two axially aligned units, one of which consists of a central tube, a coil of resistance wire wound thereon, a channel-shaped cap carried by the upper end of said tube, a truncated ogival cover having its base seated within the outer flange of said cap and its opposite end secured to said tube by expansion of the lower end thereof, a plurality of posts connected to said cap, a second U-shaped cap connected to said posts, a second central tube connected to said cap and supporting a second coil of resistance wire, a third U-shaped cap supported by the other end of said second tube, a tubular cover retained between the outer flanges of the second and third caps, outwardly extending lugs on the end of said third cap and the tubular

cover, and a tubular insulator carried by said lugs.

4. An electrical heating apparatus comprising two separate heating elements arranged in co-axial extension with aligned 70 central axial passageways, a separate imperforate cylindrical inner casing for each coil forming the wall of such passageway, a separate outer casing surrounding each coil, caps at each end of one coil and at the inner end 75 of the other connecting said inner and outer casings, mechanical and electrical connections between said elements at their adjoining ends, hollow lugs on the exposed end of one element, an insulating tube of stiff insulating material passing therethrough, a cable comprising conductors to each of said elements passing through said tube, and an enlarged insulating bushing surrounding said tube, said bushing being secured at one end 80 to said lugs and on the other end embracing said cable closely.

In testimony whereof I hereunto affix my signature this 20 day of December, 1927.
